United States Patent Office

Des. 184,625
Patented Mar. 17, 1959

184,625

LACE FABRIC OR SIMILAR ARTICLE

Roger Klauber, Great Neck, N. Y.

Application July 28, 1958, Serial No. 51,974

Term of patent 3½ years

(Cl. D47—6)

Fig. 1.

Fig. 2.

Fig. 1 is a top plan view of a lace fabric or similar article, showing my new design which is repeated in the vertical and horizontal directions; and

Fig. 2 is a fragmentary view showing a portion within the dotted lines in Fig. 1, enlarged.

I claim:

The ornamental design for a lace fabric or similar article, substantially as shown and described.
